UNITED STATES PATENT OFFICE.

THOMAS J. McCARTHY, OF NEWARK, NEW JERSEY.

ENGINE PRIMER FOR AUTOMOBILES.

1,418,591.

Specification of Letters Patent. Patented June 6, 1922.

Application filed September 6, 1919. Serial No. 322,144.

To all whom it may concern:

Be it known that I, THOMAS J. McCARTHY, a citizen of the United States, residing at Newark, in the county of Essex and State of New Jersey, have invented certain new and useful Improvements in Engine Primers for Automobiles, of which the following is a specification.

My invention relates to improvements in priming and decarbonizing devices for internal combustion engines.

The principal object of the present invention is the provision of means acting independent of the carburetor whereby a properly proportioned rich and thoroughly vaporized combustible mixture will be delivered to the cylinders of the engine for the initial or starting impulse and until the engine assumes its normal operation.

My invention further comprehends a manually operated device which will effect a saving in fuel and permit a finer or closer adjustment of the carburetor, and which may be readily attached to existing machines.

Various other objects and advantages will be apparent from the following description.

Briefly stated, my priming device comprises a small casing attached to the underside of the foot-board with the stem of the control valve projecting therethrough, the casing containing a chamber or reservoir in direct communication with the auxiliary tank of the usual vacuum feed system, and having a vaporizing channel provided with an air inlet and in direct communication with the engine manifold. The reservoir is thus always filled with a small quantity of fuel ready to be drawn into the vaporizing channel and transformed into a vapor by the impact of the inrushing stream of air as soon as it is released by pressing the foot on the valve stem, which is done as soon as the engine is turned over by the starting motor, thereby creating a suction to draw the vapor into the cylinders.

In the accompanying drawings I have illustrated my invention as embodied in a convenient and practical form, in which Figure 1 is a side elevation of an engine provided with my priming attachment; Fig. 2 is an enlarged fragmentary sectional view on the line 2—2 of Fig. 1; Fig. 3 is a partial side elevation of the engine showing a modified arrangement of the tubes or con-

duits connecting the primer with the engine manifold; Fig. 4, is a longitudinal sectional view through the priming device; Fig. 5, is a transverse section on the line 5—5 of Fig. 4; Fig. 6 is a plan view, partly in section 60 of one form of branched nipple to connect the conduit tubes to the manifold; Fig. 7 is a longitudinal sectional view of the draining device included in the vapor conduit from the radiator; Fig. 8 is a transverse 65 sectional view on the line 8—8 of Fig. 7; and Fig. 9 is a longitudinal sectional view of the pipe connector shown in the arrangement of Fig. 3.

The engine which may be any type usually employed in automobiles, is indicated conventionally at 1, having the water jacket connected to the radiator 2 and the carburetor 4 connected to the intake manifold 6. The fuel feed reservoir 10 of the usual 70 vacuum feed system now commonly employed is indicated at the back of the dash board 11. I have not considered it necessary to show the usual conduits connecting this reservoir with the supply tank at the 75 rear of the car and with the inlet nipple of the carburetor, as these are well understood.

My foot-controlled priming attachment comprises a casing 15, provided with nipples 85 16 and 17 for attachment respectively to the conduits 19 connected to the tank 10, and the conduit 20 leading to the inlet manifold.

The inlet port 16^a in the nipple 16, opens into a chamber 24, which is closed at the 90 outer end by the nut 25 and at the inner end by the valve 26 which is held against its seat by the spring 28. The chamber 24 is at all times in direct communication with the fuel reservoir 10 and consequently is 95 constantly filled with liquid fuel. The stem 27 carrying the valve 26, projects through a boss or tubular extension 29 on the upper side of the casing and is provided with a head or button 30 which projects above the 100 foot-board 32 of the car. The casing is secured to the underside of the foot-board by screws passing through ears 34 projecting from each side of the casing and is braced by the boss 29 which extends through a hole 105 in the board. The stem 27 fits accurately in the bore of the tubular boss or extension 29 and upon the inner side of the valve slides within a recess 25^a in the nut 25, the stem being thus guided at each end and ensuring 110

an accurate seating of the valve at all times.

The lower part of the casing is provided with an extended channel 37, closed at one end by a screw plug 38 and terminating at one end in an outlet 17^a extending through the nipple 17, this channel constituting a vaporizing chamber. A passage 40 connects the closed end of the channel 37 with the annular space 24^a which constitutes an extension of the chamber 24 when the valve 26 is open, but is completely closed when the valve is seated.

An air inlet port 42, intercepts the wall of the vaporizing channel in the same transverse plane with the passage 40 and at an acute angle therewith so that the inrushing jet of air will meet the fine stream of liquid fuel issuing from the passage 40, the impact causing the liquid to be broken up into a very fine spray which is thoroughly mixed with the air as it passes through the channel, being substantially converted into a vapor as it enters the conduit 20. To prevent the ingress of dust and dirt the air inlet is preferably provided with a perforated cap or screen 45.

The conduit 20 is preferably led into the manifold 6 adjacent each end and may be provided with a Y-connector 47 from which the branches 20^a lead to the threaded nipples 48, tapped into the walls of the manifold. In order that the vaporized priming mixture may be discharged at the most effective points I prefer to lead the vapor fuel from the nipples to a point adjacent the inlet valves 49 by tubes 50 projecting within the manifold as indicated in Fig. 2.

The operation of my improved priming device will be understood from the foregoing detailed description of the structural parts. When it is desired to start the car, the starting motor is actuated to turn the engine over, the movement of the pistons creating a suction within the cylinders. The button 30 is then depressed to open the valve 26 and permit the fuel to be drawn from the chamber 24 through the passage 40, where it impacts with the jet of air entering through the inlet 42. This causes the liquid to be broken up into a fine spray and as it mixes with the air it becomes thoroughly vaporized in passing through the channel 37 forming a highly explosive mixture ready to explode as soon as it is subjected to the spark within the combustion space in the engine cylinders. The engine, therefore, receives successive impulses in the cylinders instantly without waiting for the formation of an explosive mixture from the carburetor and before this takes place the engine is operating under its own power thereby greatly relieving the starting motor. In fact the starting with my priming device seems to be almost instantaneous. The chamber 24 will be immediately refilled from the reservoir so that the

primer will be ready for another priming operation if it should be necessary for any reason.

It is advantageous to introduce a certain amount of air into the manifold auxiliary to the fuel mixture coming from the carburetor. This apparently furnishes the oxygen necessary to more complete combustion within the cylinders and not only decreases the carbon deposit but to a certain extent increases the power obtained. I have, therefore, arranged the air inlet 42 upon the engine side of the valve 26, so that after the priming operation said inlet will serve as an auxiliary air supply. The importance of this feature will be appreciated by those familiar with the operation of internal combustion engines.

It is well known that it is desirable to introduce a small amount of steam or vapor into the fuel mixture since it has the effect of decreasing the deposit of carbon and possibly other advantageous features. While it is not an essential adjunct to my priming device, I have provided means for introducing the vapor which rises from the water in the radiator into the manifold through the same connections which conduct the priming mixture. This may be done by connecting the tube 60, which receives the vapor or steam from the upper space in the radiator, to one of the branches of a Y nipple 48, as illustrated in Figs. 1 and 6, or by first uniting the conduits 20 and 60 by a double branched connector 62 as indicated in Figs. 3 and 9, from which the mixed vapor and fuel intermingle and flow into the manifold through the branches 20^a.

One of the difficulties heretofore encountered in the introduction of vapor has been due to the freezing of the condensed water in the tube after the engine has cooled down in cold weather. To obviate this difficulty I introduce into the tube or conduit 60, a valved drain 65 which is provided with a drip nipple 65^a having a ball 67 which rolls against a stop pin 68 when the engine is not in operation, allowing any water to run out of the outer open end of the nipple. During the operation of the engine the suction pulls the ball inwardly against its seat, thereby closing the drip opening. In order that the ball may roll directly against its seat the bore of the nipple is provided with guide ribs 69.

My improved priming device is simple in structure and is easily installed or applied to engines as commonly constructed and has proven to be a valuable adjunct to the self starting mechanism, greatly reducing the effort required and effecting a material saving of the batteries.

I claim:

1. A foot-board engine primer for automobiles, comprising an engine having an intake manifold, a footboard on which said

- primer is mounted, a casing having a chamber provided with an inlet port adapted to be directly connected to a source of liquid fuel to maintain the chamber full of fuel, a 5 vaporizing channel, a passage connecting said chamber and said channel, a spring-pressed valve operating within said chamber to normally close said passage, said valve having a stem extending through the casing and adapted to project above the foot-board, an air inlet intercepting said channel in alinement with said passage and oblique thereto, and a conduit connecting said vaporizing channel with the engine manifold. 10
- 15 2. A foot-board engine primer for automobiles, comprising an engine having an intake manifold, a footboard on which said primer is mounted, a casing having a chamber provided with an inlet port adapted to be directly connected to a source of liquid fuel to maintain the chamber full of fuel, an outlet port communicating with a vaporizing channel in said casing, an air inlet intercepting said channel, a normally seated valve operating within said chamber to close 20
- 25
- said outlet port, said valve having a stem projecting through the casing and adapted to extend above the foot-board, and a conduit connecting said vaporizing channel with the engine manifold. 30
3. The combination with an explosive engine having the usual cylinders, inlet manifold and carbureter, provided with a fuel reservoir supplying the carbureter, of a priming device having a chamber to contain 35 liquid fuel for priming the cylinder and connected by a gravity feed to said reservoir to maintain it filled with fuel a footboard on which said priming device is mounted, a vaporizing channel connected by a conduit 40 with the inlet manifold, a passage connecting said chamber and said channel, an air inlet intercepting said channel in alinement with said passage, and a normally seated valve operating within said chamber to 45 close said passage and having a stem adapted to project above the foot-board.

In testimony whereof I affix my signature.

THOMAS J. McCARTHY.
